F. MANKEY.

MOLDING.

No. 16,957.

Patented Oct. 26, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,957, dated October 26, 1886.

Application filed July 1, 1886. Serial No. 206,874. Term of patent 7 years.

To all whom it may concern:

Be it known that I, FREDERICK MANKEY, of Williamsport, Lycoming county, Pennsylvania, have invented and produced a new and original Design for Ornamental Trim or Moldings, of which the following is a specification, reference being had to the accompanying photograph, forming part hereof.

My design relates to an ornamental trim or molding in the form of a band or bar; and it consists in the configuration thereof, substantially as represented.

One edge, A, of the band or bar is straight. The opposite edge is curved in regular scallops or convexities B. On the face of the bar, and proceeding from the points of junction of the scallops B, and continuing to the opposite edge, are curved grooves or channels C. Also, on the face of the bar, and between said grooves, are circular recesses D, and in proximity to said recesses, so as substantially to diverge therefrom, are lenticular depressions E F G.

The depressions E are parallel to said edge. The depressions F G stand diagonally to said edge.

25

I claim—

1. The design for an ornamental trim or molding, substantially as shown and described, which consists of the scallops or convexities A on one edge of the trim, the opposite edge 30 being straight, the curved grooves or channels C, and the lenticular depressions E F G.

2. The design for an ornamental trim or molding, substantially as herein shown and described, which consists in the scallops or 35 convexities A on one edge of the trim, the opposite edge being straight, the curved grooves or channels C, the lenticular depressions E F G, and the circular recesses D.

FREDERICK MANKEY.
